OIL GAS BURNER.
APPLICATION FILED DEC. 10, 1918.

Patented Mar. 29, 1921.

2 SHEETS—SHEET 2.

UNITED STATES PATENT OFFICE.

JAMES P. HORGAN, OF WOBURN, MASSACHUSETTS, ASSIGNOR TO THOMAS HOOPER, OF NEW YORK, N. Y.

OIL-GAS BURNER.

1,372,695.

Specification of Letters Patent. Patented Mar. 29, 1921.

Application filed December 10, 1918. Serial No. 266,070.

To all whom it may concern:

Be it known that I, JAMES P. HORGAN, a citizen of the United States, residing at Woburn, in the county of Middlesex and 5 State of Massachusetts, have invented certain new and useful Improvements in Oil-Gas Burners; and I do hereby declare the following to be a full, clear, and exact description of the invention, such as will enable others skilled in the art to which it 10 appertains to make and use the same.

This invention relates to improvements in oil gas burners and has for one of its objects the provision of a device of this character which is especially adapted for application to fire boxes of various stoves and of different types and is provided with means which will cause the flames to be directed vertically and laterally so that the 15 top and sides of a stove will be heated to a high degree on a comparatively small consumption of fuel.

Another object of this invention is the provision of frames detachably connected to 25 gether which support the generating pipe or retort and burner in substantially V-shape so that an elongated fire box will be heated substantially the entire length and said frames permit of the burners and retort being separated, so that one of them can be 30 used or installed in wall stoves or stoves of the character employed to heat rooms.

A further object of this invention is the provision of means whereby the frames can 35 be adjusted to heights so that the burners can be installed in fire boxes of different heights.

A further object of this invention is the provision of an oil gas burner of the above 40 stated character, which shall be simple, durable and efficient, and which may be manufactured and sold at a comparatively low cost.

With these and other objects in view as 45 will become more apparent as the description proceeds, the invention consists in such novel features of construction, combination and arrangement of parts as will be hereinafter more fully described and claimed.

50 For a complete understanding of my invention, reference is to be had to the following description and accompanying drawings, in which:—

Figure 1 is a side elevation of an oil gas

burner constructed in accordance with my 55 invention,

Fig. 2 is a longitudinal sectional view taken on the line 2—2 of Fig. 1 illustrating priming pans on the frames,

Fig. 3 is a fragmentary plan view of 60 feed pipes for the retort,

Fig. 4 is an end elevation of one of the frames illustrating the supporting feet and legs therefor,

Fig. 5 is a transverse sectional view taken 65 through one of the retorts illustrating a strainer,

Fig. 6 is a plan view of one of the burners,

Fig. 7 is a plan view of one of the connecting plates of the frame,

Fig. 8 is a plan view of the supply tank.

Fig. 9 is an end view of a deflector.

Fig. 10 is a side elevational view partly 75 in section, illustrating a supply tank.

Referring in detail to the drawings the numerals 1 and 2 indicate as an entirety supporting frames which include horizontal portions having formed upon their ends legs 4 that depend downwardly therefrom and 80 have their free ends disposed at right angles to form supporting feet 5. The horizontal portions of the frames 1 and 2 are indented to form priming pans 6 disposed directly under burners 7 carried by the ends 85 of retorts 8. The retorts 8 include horizontal portions having one end bent upon itself and disposed thereunder and connected to the burners 7 so that the flames from the burners 7 will be directed against 90 the horizontal portions causing the fuel therein to be vaporized into gas. The other ends of the horizontal portions are disposed angularly thereto to form legs 9 which are secured within bushings 10 carried by the 95 inner ends of the frames 1 and 2. The bushings 10 have connected thereto feed pipes 11 which are adapted to extend through the walls of a fire box of a stove and connected with controlling valves 12. The controlling 100 valves 12 are connected to the ends of a T-coupling 13 which has its leg portions connected to a main feed pipe 14. The main feed pipe 14 is adapted to lead to a valve 15 carried by a tank or reservoir 16. The 105 tank or reservoir 16 is provided with a removable cover 17 and has its rear wall 18 flat so that the same can evenly bear against

- the wall of a room when the tank is supported on the wall by means of a hook 19 passed through an opening in an extension 20 formed upon said tank or reservoir.
- 5 The adjacent leg 4 of the frames 1 and 2 are provided with alining openings to receive the bolt 21 provided with a nut adapted to firmly secure the frames together and in such a manner that the legs 9 and the 10 horizontal portions of the retorts 8 will be of substantially T-shape thereby forming a device of considerable length which is adapted to be positioned lengthwise within the fire box of a stove (not shown) having 15 the feet 5 resting upon the grate usually within the fire box. Therefore, it will be noted that substantially the entire length of the fire box will be subjected to the heat from the burners 7. The burners 7 are of 20 substantially T-shaped formation as clearly shown in the drawings having central openings 22 adapted to permit the gaseous fuel to escape vertically thereby producing a vertical flame which will play against the 25 horizontal portions of the retorts and also against the top of the stove. The burners 7 are also provided with oppositely disposed horizontal openings 23 that permit the fuel to engage transversely of the device 30 so that the flames will play directly upon the sides of the fire box thus coöperating with the vertical flames in heating the entire fire box to a considerable high degree on a small consumption of fuel.
- 35 The horizontal portions of the frames 1 and 2 are provided with pairs of bolts 24 equipped with nuts adapted to extend through elongated slots 25 within connecting plates 26 whereby the frames are further secured together and when it is desired 40 to adjust the frames away from each other, the bolt 21 is removed entirely from the legs 4 and the plates 26 are then depended on to connect the frames together.
- 45 Deflectors 27 are mounted upon the horizontal portions of the retorts and are disposed directly over the burners 7 so that the vertical flames therefrom will be spread over the retorts and also over the top of the 50 stove to which the device is applied. The retorts 8 have located therein foraminous material 29 preferably constructed of aluminum for the purpose of acting as strainers to prevent the burners and retorts 55 from carbonizing.
- The application of my invention to a cook stove or range is as follows:
- The frames 1 and 2 carrying the retorts and burners in substantially V-shaped formation are placed within the fire box of a 60 stove or range lengthwise. The frames 1 and 2 are then adjusted so as to evenly distribute the burners and retorts within the fire box by releasing the nuts upon the bolts 65 24. After the device has been properly

assembled within the fire box, the fuel is turned on from the tank 16 supported upon the wall of the room adjacent the stove to permit it to pass into the T-connection 13 which carries the valves 12. The valves 12 70 are then opened permitting the fuel to pass into the feed pipes 11, thence into the retorts 8 and burners 7. A small amount of fuel is allowed to drain from the burners 7 into the priming pans 6. When the priming 75 pans 6 are filled or partially so with the fuel, the same is ignited which heats the burners and a portion of the retorts, causing the fuel within the same to vaporize and turn into a gas and become ignited as the 80 same escapes from the passages 22 and 23 of the burners. As the fuel escaping from the burners in a gaseous form becomes ignited, the flames play directly upon the horizontal portions of the retorts 8 and also upon the 85 top of the stove as well as against the sides of the fire box, thus it will be seen that the entire fire box is entirely heated as well as the retorts which thoroughly vaporizes the 90 fuel.

Auxiliary legs 30 are provided with elongated slots 31 which are adapted to receive bolts 32 carried by the outer legs of the frames 1 and 2. The auxiliary legs 30 have their lower ends disposed at right angles to 95 form supporting feet 33. An auxiliary leg 34 similar in construction to the auxiliary legs 30 are secured between the inner legs 4 of the frames 1 and 2 by the bolts 21 so that when it is desired to apply or install the 100 device in fire boxes of considerable height, the auxiliary legs are attached to the legs of the frames 1 and 2 so that the burners and retorts are supported in close proximity to the top of the stove or in a position practical to the use of the device within fire 105 boxes.

From the foregoing, it will be noted that means is provided wherein the device can be installed within fire boxes of different 110 heights and lengths by simply adjusting the auxiliary legs upon the main legs of the frame and adjusting the frames toward and from each other.

To install my invention upon a household 115 stove used for heating rooms and which does not require a double burner arrangement, the frames are separated by removing the bolts 24 and plates 26, also detaching the inner legs 4 of the frame by removing 120 the bolts 21. A single frame, retort and burner then can be installed within the fire box of the last named type of stove.

While I have shown and described the preferred embodiment of my invention, it 125 will be understood that minor changes in construction, combination, and arrangement of parts may be made without departing from the spirit and scope of the invention as claimed.

Having thus described my invention, what I claim is:—

A device of the character set forth comprising a supporting frame, a bushing secured to the frame at one end thereof, a retort including a horizontal portion having one end bent angularly and secured to the bushing and having its other end curved upon itself and disposed in a plane below the horizontal portion, a burner connected

to the last named end of the retort, a strainer within the retort, and means connected to the bushing for supplying fuel to the retort.

In testimony whereof I affix my signature 15 in presence of two witnesses.

JAMES P. HORGAN.
